(57) **CLAIM**

The ornamental design for a motion lamp, as shown and described.

DESCRIPTION

FIG. 1 is a front elevational view of the motion lamp of FIG. 1, which is a mirror image of a rear and side elevational view (not shown);

FIG. 2 is a perspective view of the motion lamp showing my new design;

FIG. 3 is a top plan view of the motion lamp of FIG. 1; and, FIG. 4 is a bottom plan view of the motion lamp of FIG. 1.
